CLAIM

The ornamental design for a hanging decoration, as shown and described.

DESCRIPTION

FIG. 1 is a perspective view of a hanging decoration showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof, with broken lines shown for illustrative purposes only, and forming no part of the claimed design.

The bell hanging decoration claimed is for hanging on a Christmas tree or hanging indoors or outdoors as a decoration article. The hanging decoration according to my design is a bell in a flat circular shape, and having a raised line disposed transversally across the middle of the surface of the bell, a plurality of concave surfaces disposed on an external surface of the bell, and a design pattern of crest shaped lines formed at the intersection of two concave surfaces so that many concave and convex lines are formed on the surface of the bell.
